UNITED STATES PATENT OFFICE

2,506,245

OVERSHOE WITH LAPPING VAMP
AND TOE PORTIONS

Henry Stanton, Dallas, Tex.

Application December 19, 1946, Serial No. 717,255

2 Claims. (Cl. 36—7.2)

1

This invention relates to overshoes.

An object of this invention is to provide a protecting covering for lady's shoes which is of flexible construction and will protect shoes from rain, snow, mud or the like.

Another object of this invention is to provide an overshoe which is made of transparent, flexible and elastic material so that the shoe will be visible through the overshoe.

A further object of this invention is to provide a flexible and elastic overshoe which is made out of composition material, such as plastic material or the like, and which can be made light in weight so that when the shoe is not worn it can be folded into a small compact package for placing in a pocketbook or the like.

With the above and other objects in view, my invention consists in the arrangement, combination and details of construction disclosed in the drawings and specification, and then more particularly pointed out in the appended claims.

In the drawings:

Figure 1 is a detail side elevation of an overshoe constructed according to an embodiment of this invention, mounted on a shoe,

Figure 2 is a plan view of the overshoe,

Figure 3 is a sectional view taken on the line 3—3 of Figure 2, showing the overshoe in applied position,

Figure 4 is a sectional view taken on the line 4—4 of Figure 1,

Figure 5 is a fragmentary sectional view taken similar to Figure 4, but showing the fastening means in released position,

Figure 6 is a fragmentary sectional view taken on the line 6—6 of Figure 3.

Referring to the drawings, the numeral 10 designates generally a conventional lady's shoe which has a relatively high heel 11. A flexible and elastic overshoe generally designated as 12 is adapted to engage about the shoe 10, being formed with an open rear heel portion whereby the heel 11 may project through the overshoe. The overshoe 12 includes a pair of quarters 13 which are formed integral with each other and the quarters 13 have merging therewith a heel or rear portion 14 which engages about the rear portion of the shoe 10.

The quarters 13 are formed with overlapping box or toe portions 15 and 15a which are adapted to be secured together by means of fastening members 16 in the form of snap fasteners or the like. The forward portions of the quarters 13 and the toe or box portions 15 and 15a are formed with inwardly extending flanges 17 and 18, which

2

are secured by cementitious material or the like to the inner side of a sole 19. The sole 19, at its outer edges, is formed with upwardly extending flanges 20 and 21 which are secured by cementitious material or the like to the outer lower sides of the quarters 13 and box members 15 and 15a.

The forward end of the sole 19 includes an upwardly extending flange or extension 22 which tapers upwardly and rearwardly and substantially merges with the outer toe portion of the box member 15a. The bottom of the sole 19 is formed with transversely extending ribs or tread members 23 and the rear portion of the sole 19 extends upwardly and rearwardly as indicated at 24 and terminates at a point forwardly from the heel 11 of the shoe 10.

The quarters 13 are provided with inwardly extending arcuate members 25 which are disposed in spaced apart confronting relation and are connected together by an elastic connecting member 26. In this manner the rear instep and heel portion of the overshoe is substantially open but is held against upwardly creeping movement on the heel of the shoe by the elastic 26, and the inwardly extending members 25.

The overshoe hereinbefore described is adapted to be formed out of flexible and elastic plastic material and is preferably transparent so that the shoe encased thereby will be visible through the overshoe. The overshoe is formed of relatively thin material as to the uppers and the toe or box portion so that the overshoe can be readily folded into a relatively small package. In this manner the overshoe can be carried in a pocketbook or like holder.

I do not mean to confine myself to the exact details of construction herein disclosed, but claim all variations falling within the purview of the appended claims.

What I claim is:

- An overshoe comprising an upper including a pair of opposite side members, an inwardly extending forward portion formed on each of said members, one of said portions overlapping the other to provide a toe and vamp, a half sole member having the toe and side edges thereof secured to the bottom edges of said forward portions, free edges on said forward portions diverging forwardly from a point of juxtaposition at the center of the top of the vamp and extending to said bottom edges, a plurality of inter-engagable fastening means carried by the free edge of said one portion and spaced therealong to a point close to the bottom end thereof and by

the underlying forward portion, and a heel engaging member formed integral with the rear edges of each of said side members.

2. An overshoe as set forth in claim 1 including additional inter-engageable fastening means carried by the free edge of said underlying forward portion, intermediate the length thereof, and by said overlapping forward portion.

HENRY STANTON.
